(57) CLAIM

The ornamental design for a delivery truck box, as shown and described.

DESCRIPTION

FIG. 1 is a first perspective view of a delivery truck box, taken from the front;

FIG. 2 is a second perspective view of the delivery truck box of FIG. 1, taken from the back;

FIG. 3 is a right-side view of the delivery truck box of FIG. 1;

FIG. 4 is a left-side view of the delivery truck box of FIG. 1;

FIG. 5 is a front view of the delivery truck box of FIG. 1; FIG. 6 is a back view of the delivery truck box of FIG. 1; and,

FIG. 7 is a top view of the delivery truck box of FIG. 1. The broken lines showing environmental portions of the truck, and features of the delivery truck box, form no part of the claimed design.

1 Claim, 7 Drawing Sheets
